UNITED STATES PATENT OFFICE.

JOSEPH A. WADDELL, JR., OF SCRANTON, PENNSYLVANIA, ASSIGNOR TO SPENCER HEATER COMPANY, OF SCRANTON, PENNSYLVANIA, A CORPORATION OF PENNSYLVANIA.

WATER-JACKET FURNACE.

1,063,088.

Specification of Letters Patent.

Patented May 27, 1913.

Application filed August 5, 1912. Serial No. 713,412.

To all whom it may concern:

Be it known that I, JOSEPH A. WADDELL, Jr., a citizen of the United States, residing at Scranton, in the county of Lackawanna and State of Pennsylvania, have invented certain new and useful Improvements in Water-Jacket Furnaces, of which the following is a specification.

The present invention relates to furnaces of the same general type as that forming the subject matter of the Letters Patent of David Boies and Joseph A. Waddell, Jr., No. 1,045,668, issued November 26, 1912. Said Letters Patent disclose an inclined 15 grate, a fuel magazine located above the high portion of the grate and a combustion chamber over the main body of the grate; the magazine and combustion chamber being constructed of hollow boiler sections, each 20 comprising an inner wall formed with a recess, providing one side of the magazine, and an inwardly inclined and downwardly extending water leg; there being a suitably related opposite magazine wall, water legs 25 being disposed at such an angle as to form a constricted fuel outlet from the magazine presented toward the high point of the grate; the boiler sections being also formed with an outer furnace wall, the lower portion 30 of which extends downwardly and inwardly to provide the outer wall of the combustion chamber and located to leave between it and the inwardly inclined depending water leg, a relatively large combustion 35 chamber located over the main body of the grate. In the illustrative embodiment of the apparatus selected in Letters Patent No. 1,045,668, the grate is of the double inclined type presenting two surfaces extending 40 downward and outward symmetrically on opposite sides of a longitudinal crest or ridge, and both walls of the magazine constitute inner portions of the water jacket and have outer furnace walls related thereto 45 in position to provide duplicate combustion chambers. This arrangement is well adapted for furnaces above certain dimensions, but involves certain complications when embodied in furnaces of certain reduced 50 capacities.

The object of the present invention is to provide a construction in which the advantages of the above defined construction may be realized, measurably at least, in a water 55 jacket furnace of relatively small dimen-

sions, and consists primarily in embodying all the grate surface in a single incline on one side of the crest, locating the magazine to one side of the furnace, with its discharge mouth above said crest, with the combustion 60 chamber, and the circulating passages for the hot gases, at the other side of the furnace; the wall related to the inner magazine wall, to complete the magazine, being in this instance, one of the outer furnace 65 walls which extends downwardly from the mouth of the magazine to provide an abutment for the high portion of the fire-bed and, preferably, also extending downwardly a distance corresponding to the other wall 70 of the fire-box and there provided with circulating connection with said other wall and fire-box. This arrangement not only involves the advantages of adapting the general principles in a furnace with a single 75 inclined grate, but develops certain increase in the heating area, as will be hereinafter more fully described.

The accompanying drawing represents a transverse section of the improved water 80 jacket furnace, the section being taken in the plane passing between two sections of which the furnace is to be built up.

A represents the magazine, B the fire-bed, C the combustion chamber and G the grate. 85 The mouth *a* of the magazine A is above the high portion of the grate G, and at such distance that the natural flow of the fuel of proper size, will develop an inclined surface of the fire-bed B, substantially parallel to 90 the surface of the grate so as to produce a fire-bed of uniform depth and leave the combustion chamber of relatively large dimensions extending above the fire-bed on lines approximately perpendicular thereto, so 95 that there will be plenty of room for the distilled gases to intermingle with air and burn.

The furnace is built up of sections 1, each constructed with a top arch 2 and an intermediate arch 3, providing two separated horizontal flues 5 and 6 which will be in communication at their ends, as is common in furnaces of this type, the arches 2 and 3 of the sections being made to abut so as to 100 prevent communication between the flues 5 and 6 except at the end. Each section is further provided with an arch 4, but the sides of these arches are not in abutment so that the 105 products of combustion pass vertically be- 110

tween them. The arch 3 is connected with the arch 2 by the converging up-takes 7, while the high point in each arch 4 is connected with the arch 3 above it by a single 5 up-take 8, so that aside from increasing the heating surface, the water rises, as its temperature increases, from the high point of each arch to the arch above it. This also has the effect of drawing the preliminarily 10 heated water from the lower portion 9^a of the furnace wall 9, which provides the outer wall of the fire-box, and also from the rear furnace wall 10, 10^a, passing through the water bridge 10^b which is of less width than 15 the members 10^a and 11^a, the flow being downward from the upper portion and upward from the lower portion of said rear wall. The aforesaid connections also draw the preliminarily heated water from the relatively 20 cool inner wall 11 of the magazine A and from the depending water leg 11^a of said magazine.

12 and 13 represent front and rear base channels which are connected at one end by 25 a cross channel 14 (shown in dotted lines) and which receive the return pipe 15 of the circulating system.

16 represents the upper circulating connection between the sections through which 30 the hot water is supplied.

I claim:—

1. A boiler furnace comprising a single incline grate, a fuel magazine above the high portion of the grate and a combustion chamber 35 extending upwardly and outwardly from the main body of the grate; said magazine and combustion chamber being constructed of hollow boiler sections, each comprising three upwardly extending walls, to wit, an outer wall extending vertically from 40 the high point of the grate and forming one of the outer walls of the furnace, an intermediate wall terminating at a point adjacent to said vertical outer wall but above the sur-

face of the grate and forming with said vertical outer wall a magazine with a restricted opening discharging upon the high portion of the grate; and a second outer wall extending upwardly and outwardly from the lower portion of the grate and forming with 45 said intermediate wall a combustion chamber approximately perpendicular to the inclined surface of the grate; there being arch walls extending between the intermediate wall and the outwardly inclined outer wall; 50 all of said walls being hollow to provide passages for a heat conveying medium. 55

2. A sectional boiler furnace comprising a single incline grate, a combustion chamber substantially perpendicular to the inclined surface of the grate, and a magazine having a restricted discharge opening vertically above the high portion of the grate; the boiler of said furnace being constructed of sections, each formed with an outer magazine wall extending vertically upward from the high point of the grate, an outer combustion chamber wall extending upwardly and outwardly from the lower point of the grate, and an intermediate wall dividing the upper part of the combustion chamber from the magazine and extending upwardly from a point above the grate and adjacent to the outer magazine wall; the upper portion of each of said walls being deflected to provide a vertical portion extending to the top of the furnace and there being hollow arch walls connecting the intermediate wall with the outer combustion chamber wall, and up-take 70 passages extending from high points of the 75 arch walls to the walls above the same.

The foregoing specification signed at Scranton, Pa., this twenty-third day of July, 1912.

JOSEPH A. WADDELL, JR.
